(57) **CLAIM**

I claim the ornamental design for a gate hinge, as shown and as described.

DESCRIPTION

FIG. 1 is a perspective view of the gate hinge.

FIG. 2 is the front view of the gate hinge.

FIG. 3 is a back view of the gate hinge.

FIG. 4 is a side view of the gate hinge.

FIG. 5 is the other side view of the gate hinge.

FIG. 6 is a top view of the gate hinge.

FIG. 7 is bottom view of the gate hinge.

FIG. 8 is a perspective view of the gate hinge shown reduced in scale;

FIG. 9 is a reduced in scale perspective view of an alternative configuration of use of the gate hinge, showing marker lines where the FIG. 10 was taken from; and,

FIG. 10 is an enlarged view of the gate hinge shown within the marker in FIG. 9 thereof.

The broken lines represent an environment of use for the gate hinge and form no part of the claim.
